US00D875969S

(12) **United States Design Patent** (10) **Patent No.:** **US D875,969 S**
(45) **Date of Patent:** **** Feb. 18, 2020**

(54) **THRESHOLD CAP**(71) Applicant: **Endura Products, Inc.**, Colfax, NC (US)(72) Inventors: **Tomasz Jaskiewicz**, Oak Ridge, NC (US); **Michael K. Mitchell**, Winston-Salem, NC (US)(73) Assignee: **Endura Products, Inc.**, Colfax, NC (US)(**) Term: **15 Years**(21) Appl. No.: **29/601,563**(22) Filed: **Apr. 24, 2017****Related U.S. Application Data**

(63) Continuation-in-part of application No. 29/534,779, filed on Jul. 31, 2015, which is a continuation-in-part of application No. 14/717,194, filed on May 20, 2015, now Pat. No. 9,528,314.

(51) **LOC (12) Cl.** ..... **25-02**(52) **U.S. Cl.**USPC ..... **D25/48.2**(58) **Field of Classification Search**USPC D25/48.1–48.4, 48.8, 55, 60, 119–125, D25/164, 199

Primary Examiner — Leanne Was-Englehart*(74) Attorney, Agent, or Firm* — Womble Bond Dickinson (US) LLP(57) **CLAIM**

The ornamental design for a threshold cap, as shown and described.

DESCRIPTION

FIG. 1 is a profile view of our new design; FIG. 2 is a top perspective view thereof; and, FIG. 3 is a bottom perspective view thereof.

The views not shown form no part of the claimed design. The dash-dot lines in the figures adjacent to the shaded areas represent unclaimed boundaries of the claimed design. The dash-dot lines in the figures represent portions and environmental elements that form no part of the claimed design.
